UNITED STATES PATENT OFFICE.

H. K. SCHAUCK, OF BENVILLE, INDIANA.

IMPROVED COMPOSITION FOR ROOFING.

Specification forming part of Letters Patent No. **59,462**, dated November 6, 1866.

To all whom it may concern:

Be it known that I, H. K. SCHAUCK, of Ben-
ville, in the county of Jennings and State of
Indiana, have invented a new and useful Im-
provement in Composition for Plastic Roofing;
and I do hereby declare the following to be a
full and complete description of the ingre-
dients, with the proportions of each and the
manner of compounding the same, forming my
improved plastic roofing composition, suffi-
cient to enable any person of competent skill
in the art to make and use my invention.

In the employment of most of the roofing
compositions the use of tarred paper or some
other textile substance is required to receive
the composition and form the complete roof.
This adds largely to the cost of the covering,
both in material and labor. The design of my
improved composition is to be used upon the
naked sheathing of the roof, or, still more ap-
propriately, upon a foundation made of narrow
strips of sufficient thickness, say about one
inch, nailed to the rafters, as laths are used
for plastering, with a small space between
each.

The elements of my improved roofing com-
position consist of crude coal-tar, common blue
clay, and flowers of sulphur, in the following
proportions, to wit: twelve (12) parts dry and
finely-pulverized blue clay, one (1) part flowers
of sulphur, mixed and incorporated with a suf-
ficient quantity of common crude coal-tar to
form a plastic mass of convenient consistency
to be handled and applied to the roof with an

ordinary trowel. The clay and the sulphur
are first mixed in the proportions above stated,
and then moistened with the coal-tar and
thoroughly incorporated therewith, enough of
the latter being used to give to the whole the
proper consistency, as above stated. All the
operations of mixing and using the composi-
tion may be performed while the materials are
in the cold state, or at a temperature not much
above 100°. In no case should the tar or the
composition be boiled.

The composition may be applied to the roof
with an ordinary trowel, or any convenient
tool, after the manner of applying plastering.
The substance will, in a very short time, harden,
so that it can be walked upon. At the same
time it will retain sufficient plasticity to ac-
commodate the ordinary vibrations to which
roofs are exposed without cracking. It will
not become fluid from the heat of the sun and
run, nor will it shrink and crack.

Having fully described my improved roofing
composition, what I claim as my invention,
and desire to secure by Letters Patent of the
United States, is the following:

A roofing composition composed of the sub-
stances herein specified, in the proportions
and compounded in the manner substantially
as described.

H. K. SCHAUCK.
